(57) **CLAIM**

The ornamental design for a serving platter system as shown and described.

DESCRIPTION

FIG. 1 is a top perspective view of the serving platter system with the cutting board portion separated from the platter portion, showing an embodiment of my new design.

FIG. 2 is a top view of the serving platter system of FIG. 1. FIG. 3 is a bottom view of the serving platter system of FIG. 1.

FIG. 4 is a front view of the serving platter system of FIG. 1 with the cutting board portion separated from the platter portion.

FIG. 5 is a section view showing a bottom view of the cutting board portion of the serving platter system of FIG. 1. FIG. 6 is a section view showing a top view of the platter portion of the serving platter system of FIG. 1.

FIG. 7 is a rear view of the serving platter system of FIG. 1 with the cutting board portion separated from the platter portion.

FIG. 8 is a left-side view of the serving platter system of FIG. 1 with the cutting board portion separated from the platter portion.

FIG. 9 is a right-side view of the serving platter system of FIG. 1 with the cutting board portion separated from the platter portion.

FIG. 10 is a bottom perspective view of the serving platter system of FIG. 1 with the cutting board portion separated from the platter portion; and,

FIG. 11 is a top perspective view of the serving platter system of FIG. 1.

The broken lines in the figures show portions of the serving platter system and/or environment that form no part of the claimed design.

While the accompanying drawings include broken lines that form no part of the claimed design, the broken lines provide written description of prospective embodiments that are claimed when one or more of the broken lines are amended to solid lines. Similarly, while the solid lines in the drawings form part of the claimed design, the solid lines provide
